UNITED STATES PATENT OFFICE.

ARTHUR J. SWEET, OF MILWAUKEE, WISCONSIN.

LIGHT-CONTROLLING-DEVICE HOLDER.

1,367,638.

Specification of Letters Patent.

Patented Feb. 8, 1921.

Application filed January 8, 1918. Serial No. 210,844.

To all whom it may concern:

Be it known that I, ARTHUR J. SWEET, citizen of the United States, residing at Milwaukee, Wisconsin, have invented certain new and useful Improvements in Light-Controlling-Device Holders; and I do hereby declare the following to be a full, clear, and exact description of the invention, such as will enable others skilled in the art to 10 which it appertains to make and use the same.

My invention relates to lighting fixtures, and more particularly to appliances for securing reflectors, diffusing bowls, or other 15 types of light-controlling devices to piping, rods or the like. For this general purpose, my invention aims to provide a holder which will permit of raising or lowering the light-controlling device relative to the lamp; 20 which can readily be shipped in an exceedingly compact form when disassembled; which can speedily be assembled and secured in position, and easily adjusted as to its position; which will be neat and firm when in- 25 stalled, and which in some embodiments of the invention will eliminate the use of small screws or other petty fastening elements likely to jar loose or to be lost. More par- 30 ticularly, my invention aims to provide a holder in which the arms are entirely detachable from the securing means which clamp them to the fixture stem or other sup- port, in which these arms will be spaced from each other by simple and effective 35 means, and in which the same securing means may be used interchangeably with arms of different lengths or shapes, thereby enabling substitutions to be made without removing the securing means or other fix- 40 ture parts from the fixture. Furthermore, my invention aims to provide a holder of a spider type, in which the arms afford direct connection with both the support and the light-controlling device carried by the arms; 45 in which the arms are simultaneously se- cured to, or loosened from, the support by a simple manipulation of a single element; and in which a partial loosening of the se- 50 curing means will permit the arms to be rocked upon the fixture stem without de- taching the arms, thereby enabling the outer ends of the arms to be swung out of engage- 55 ment with the light-controlling device. In this last aspect, my invention is intended to provide a holder in which the ends of the

arms associated with the light-controlling device can readily be moved into and out of their normal positions by bodily rocking these arms, thereby permitting the use of inflexible arms which may more easily be 60 made of the strength required for supporting heavy diffusing bowls or refractors and which arms may be interchanged with others whenever the lighting requirements make it desirable to substitute some other 65 size or shape of light-controlling device.

With the above described and other ob- jects in mind, I am describing various em- bodiments of my invention in the following specifications, and am illustrating the same 70 in the accompanying drawings in which—

Figure 1 is a fragmentary elevation showing one desirable form of my invention as employed in supporting a light-controlling- 75 device of a bowl type.

Fig. 2 is an enlarged elevation of a part of the fixture stem and of the holder por- tions adjacent thereto.

Fig. 3 is a transverse section through Fig. 2 along the line 3—3.

Fig. 4 is an enlarged and fragmentary section through Fig. 2 taken along the line 4—4 of Fig. 3.

Fig. 5 is a section similar to Fig. 3 but taken through an embodiment of my inven- 85 tion in which the arm spacing and alining element constitutes a separate part and is not integral with the pipe to which the holder is clamped.

Fig. 6 is a perspective view of a spacing 90 and alining element suitable for use with the embodiment of Fig. 5.

Fig. 7 is a perspective view of an embodi- 95 ment of my invention in which the spacing and alining element is fast upon the arm and is threaded.

Fig. 8 is a transverse section similar to Figs. 3 and 5 but taken through an embodi- 100 ment of my invention in which the clamping device operates on the principle of a metal strap, and in which the spacing and alining elements are integral with the said clamping device.

Fig. 9 is an elevation of the clamping means and adjacent arm portions of Fig. 8 105 as attached to a pipe.

Fig. 10 is a fragmentary vertical section through holder portions similar to those of Fig. 9 but with a tongue on the clamp inter- 110 locking with a notch on a holder arm.

Fig. 11 is a fragmentary elevation of the holder parts of Fig. 10 when in use.

In accomplishing the purposes of my invention, after the manner illustrated in the drawings, I provide a holder of the spider-arm type employing a plurality of arms, which arms (according to an essential feature of my invention) are entirely detachable from the pipe or fixture stem 3 in some other manner than by passing them, grouped as forming the holder, over either extreme end of the said stem or over the socket. The arms may be entirely separable from the clamping means, as in Figs. 4, 9 and 10. However, they are preferably so designed with respect to the clamping means that a partial loosening of the latter will permit the entire holder to be moved lengthwise of the fixture stem (thereby permitting of a speedy and exact positioning of the light-controlling device with respect to the lamp), and will also permit the arms of the holder to be rocked about the fixture stem while still maintaining these arms partially engaged with the clamping means. Thus by partially backing off the clamping sleeve 1 of Figs. 2 and 4, the tapered thread on the latter will still remain partially engaged with the threads on the adjacent ends of the holder arms 2, but will permit each of these arms to be rocked on an imaginary axis near its threaded end, so that the other end of the arm can be thrown out of engagement with the inter-engaging portion of the light-controlling device 6, thus permitting the light-controlling-device to be removed from the holder. The action here described will be made more clear by reference to Fig. 4, which shows in full lines the arm in the position of attachment to the light-controlling-device, and in dotted lines the arm rocked back to a position of disengagement with the latter. Obviously, a similar action is possible with other forms of my invention, such as those specifically presented by Figs. 8 and 9. The interengaging surfaces of each arm 2 and the light-controlling-device 6 are preferably so formed that, even when, by the partial unclamping above described, the arm is free to rock, it is limited as to such rocking by a downward-projecting element of the light-controlling-device, so that the lower portion of the arm cannot be rocked outward into a position of disengagement with the light-controlling-device, unless the light-controlling-device is raised at the point of engagement by an amount equal in height to the said downward projection. The elemental relationship of such inter-engaging surfaces is illustrated in Fig. 4, though it will be obvious that these inter-engaging surfaces may be variously shaped, the condition of this feature of my invention being fulfilled if a downward-projecting element of the light-

controlling-device is provided at the point of inter-engagement at a greater radial distance from the fixture axis than an upward-projecting element of the arm.

If it is desired to adjust the position of the holder on the stem, it is obvious that this can conveniently be done in the partially unclamped adjustment of the holder, either with the light-controlling-device in position in the holder or with the light-controlling-device removed.

To entirely remove the spider arms, the clamping ring 1 of Figs. 1 to 4 is entirely unscrewed, to disengagement with the taper-threaded ends of the arms 2 (or with the taper-threaded spacer 8, an integral portion of arm 7, Fig. 7), the complete disengagement of the threads obviously permitting the arms to be removed; or the tightening screw of the clamping strap, Figs. 8 and 9, is entirely unscrewed, permitting the clamping strap to be so sprung open as to disengage the retaining pin and hence entirely release the arms.

From the foregoing descriptions it will be evident how, with any of the various embodiments of my invention, the arms may be removed and other arms of different sizes or types substituted, so as to be adapted to the support of a light-controlling-device of different character and proportions, without removing the socket or interrupting the lighting service. It will likewise be evident how the arms may be shipped separate from the fixture stem, and assembled with the fixture either at the time when same is installed, or subsequent thereto, as may be found desirable.

In order to securely support the light-controlling-device, and in order that the fixture present a satisfactory appearance, it is desirable that the spider-arms be properly spaced relative to each other and held in proper planes. This spacing and alining is desirably accomplished simultaneously, as for example by the longitudinal grooving on the piping or stem of Figs. 1 to 4; or the spacing and alining means may be fast upon the arm, as in Fig. 7; or a separate spacing and alining member 5 may be used, as in Figs. 5 and 6; or the same purpose may be accomplished by grooves in the clamping member 4, as in Figs. 8 and 10. Thus, it will be obvious that widely varied means may be used for accomplishing the desired spacing and alining of the arms, and I do not wish to be limited as to any particular embodiment of this feature. Likewise, while I have illustrated holders having three arms and, in the case of a threaded clamping sleeve, having threads on the arms themselves, I do not wish to be limited to these or other details of the construction and arrangement here disclosed, it being obvious that these might be modified in many ways.

without departing from the spirit of my invention.

I claim as my invention:

1. A holder for securing a light-controlling device to a fixture stem, comprising a plurality of separable arms each bearing directly against the stem at its inner end and each equipped at its outer end with an inwardly directed hook overhanging the rim 5 of the said device, and means for simultaneously clamping the said inner end arms against the fixture stem and holding the arms in such positions that their outer ends will securely engage said light-controlling 10 device.
2. A holder for securing a light-distributing device to a fixture stem, comprising a plurality of arms each having an inner end disposed substantially parallel to the fixture 15 stem and bearing directly against the latter, and single means for simultaneously clamping the said inner arm ends against the stem, the outer ends of the arms having light-controlling-device-engaging means responsive in action to the said clamping 20 means.
3. A holder as per claim 2, in combination with means for spacing the said inner arm ends circumferentially of the fixture stem.
4. A light-controlling-device holder for use with a fixture stem, comprising a plurality of separable arms each bearing at its upper end against the stem, and tightenable means for simultaneously forcing the said 25 ends of all the arms radially inward against the stem, the said means and the adjacent arm portions having interengaging formations arranged for maintaining the arms interlocked with the said means upon a partial 30 loosening of the latter to permit a simultaneous movement of the said means and of the arms longitudinally of the fixture stem.
5. A holder for securing a light-control-

ling device to a fixture stem, comprising arms separable from both of the aforesaid 45 and from each other, and means laterally engaging the arms for alining the latter in diverging planes substantially radial of the axis of said stem and for simultaneously and clampingly securing the arms directly 50 to the stem.

6. A holder for securing a light-controlling device to a fixture stem, comprising arms separable from both of the aforesaid 55 and from each other, means for alining the said arms in diverging planes substantially radial of the axis of said stem while permitting a movement of the arms longitudinally of the stem, and means for simultaneously and clampingly securing the arms directly 60 to the stem.

7. In a pendant lighting fixture, a socket-carrying stem having a portion equipped with longitudinal grooves, light-controlling-device-holding arms having portions respectively disposed in the said grooves and movable longitudinally of the latter, and means for simultaneously clamping the said arm portions directly to the said stem.

8. The combination with a pendant fixture stem, of a socket upon the end of the stem and larger in diameter than the stem, a holder member housing a part of the stem, holder arms independently and interchangeably attachable to the holder member, and 75 means associated with the holder member and the said arms for causing the former to clamp the latter upon the stem; the holder member having a bore intermediate in diameter to the said stem and socket, whereby the socket is adapted to support the holder member when the arms are detached 80 from the latter.

Signed at Milwaukee, Wisconsin, January 2, 1918.

ARTHUR J. SWEET.
